LAMINAR CLEAN AIR PROJECTOR

Douglas M. Sandefur, Los Angeles, Calif., assignor to
Sandefur Engineering Co., Inc., Lawndale, Calif., a
corporation of California

Filed Jan. 27, 1969, Ser. No. 15,531

Term of patent 14 years

Int. Cl. D23—04

U.S. Cl. D23—149

FIG. 1.

FIG. 2.

FIG. 1 is a front perspective view of a laminar clean air projector; and

FIG. 2 is a rear perspective view of a laminar clean air projector.

The surface perforations on the front and the meshing on the rear of the clean air projector are partially shown for convenience of illustration and are understood to be continuous over the respective areas.

I claim:

The ornamental design for a laminar clean air projector, as shown and described.
